(57) **CLAIM**

The ornamental design for a semiconductor module, as shown and described.

DESCRIPTION

FIG. 1 is a front view of a semiconductor module showing our new design;

FIG. 2 is a rear view of the semiconductor module thereof; FIG. 3 is a left view of the semiconductor module thereof; FIG. 4 is a right view of the semiconductor module thereof; FIG. 5 is a top side view of the semiconductor module thereof; and,

FIG. 6 is a bottom side view of the semiconductor module thereof.

The thinner lines other than a thicker line in the front view, the rear view, the left side view the right side view, the top view, and the bottom view represents a shape of a three-dimensional shape.
